poration of Illinois

Application October 31, 1946, Serial No. 706,893

17 Claims. (Cl. 171—242)

1

This invention is directed to tuning mechanisms for wave-signal translating apparatus and, particularly, to manually operable tuning mechanisms of the push-button type in which each push button is adapted selectively to adjust the tuning of a wave-signal translating apparatus such as a radio receiver to a plurality of frequencies, each of which usually comprises a predetermined frequency in any of a plurality of frequency bands. As used throughout the specification and claims, the term "plurality of frequency bands" is intended to include a plurality of discrete frequency bands, which may be adjoining or widely separated.

Manually operable tuning controls of the push-button type have been employed principally in connection with radio receivers which receive signals within a single frequency band. Their use in receivers which are adapted to receive signals in any of a plurality of frequency bands, however, has not been extensive due, in general, to the multiplicity of push buttons and associated mechanisms which are required to afford tuning to a sufficient number of individual frequencies in each band. In view of the present trend toward multiband receivers, particularly those for selectively translating both amplitude-modulated and frequency-modulated signals, it would be very desirable to employ in a receiver a push-button tuning mechanism which utilizes a plurality of push buttons, each of which may be utilized to tune the receiver to a preselected frequency in any of the several frequency bands. For some installations, it would also be desirable additionally to include a continuously variable manual tuning control which could be operated to tune the receiver over the entire frequency range in any of the above-mentioned bands.

It is an object of the invention, therefore, to provide a new and improved tuning mechanism of the push-button type for a wave-signal translating apparatus in which each push button is adapted by the actuation or movement thereof to tune the apparatus to any preselected frequency within each of a plurality of frequency bands.

It is another object of the invention to provide a new and improved tuning mechanism of the push-button type for a wave-signal translating apparatus in which the number of push buttons and co-operating mechanisms required to adjust the tuning of the apparatus to any preselected frequency within each of a plurality of frequency bands is extremely few.

2

It is a further object of the invention to provide a new and improved tuning mechanism of the push-button type for a wave-signal translating arrangement, which mechanism is relatively simple in construction, compact in arrangement, and accurately adjustable.

In accordance with a particular form of the invention, a tuning mechanism for a wave-signal translating apparatus including adjustable means for tuning the apparatus to a plurality of preselected frequencies comprises a plurality of groups of actuating members, each member thereof being movable independently of any other member from a nonoperative position to an operative position and adapted when moved to the operative position thereof to effect a preselected adjustment of the tuning means. The tuning mechanism also includes a manually operable element for each of the groups of actuating members, each of the manually operative elements being adapted individually to engage and to move any one of the actuating members of an individual group thereof from its nonoperative position to its operative position for selectively adjusting the tuning means to a corresponding preselected frequency. The tuning mechanism additionally includes means for latching any actuated member in the aforesaid operative position thereof, and means on each of the actuating members for tripping the latching means and releasing any actuated member which is latched in the operative position thereof when any actuating member is operated from the nonoperative position thereof to the operative position thereof. The tuning mechanism further includes means for selectively establishing operative relations between each of the manually operable elements and any selected one of the actuating members of a group individual thereto so that the tuning means may be selectively adjusted to any of a plurality of preselected frequencies by each of the manually operable elements. The tuning mechanism also includes means controlled by the means for establishing operative relations for tripping the latching means and releasing any actuated member latched in the operative position thereof prior to the establishment of operative relations between the actuating members and the manually operable elements.

For a better understanding of the present invention, together with other and further objects thereof, reference is had to the following description taken in connection with the accompanying drawings, and its scope will be pointed out in the appended claims.

Referring now to the drawings, Fig. 1 is a plan view of a tuning mechanism embodying the present invention, with portions broken away to show details of construction; Fig. 2 is a plan view of certain portions which were omitted in the illustration of Fig. 1; Fig. 3 is a sectional view along the line 3-3 of Fig. 1; Fig. 4 is a fragmentary perspective view illustrating representative operating members of the tuning mechanism; and Fig. 5 is an enlarged plan view showing certain details of construction.

Referring now more particularly to Figs. 1-3, inclusive, of the drawings, the tuning mechanism for a wave-signal translating apparatus includes a framework 10 which supports a plurality of adjustable tuning means 11, 11 and 11', 11' (Figs. 2 and 3) for tuning the apparatus to a plurality of preselected frequencies within each of a plurality of frequency bands, specifically a pair of frequency bands. An upper set of tuning means 11, 11 is employed to tune the apparatus in one frequency band while a lower set of tuning means 11', 11' is utilized to tune the arrangement in the other of the pair of frequency bands. Each tuning means comprises a variable inductance device including a winding 12, which is rigidly supported by a bracket 14 on the framework 10, and a magnetic core 13, the position of which within the winding may be altered in a manner to be described subsequently to vary the inductance thereof. Each of the upper set of tuning means 11, 11 is connected to suitable circuits of a wave-signal translating apparatus such as a well-known multiband receiver through one section of each of a set of switches 15, 15 (see Fig. 2) while each of the lower set of tuning means 11', 11' is connected to suitable circuits of the receiver through another section of each of the set of switches 15, 15. Since the tuning devices 11, 11 and 11', 11' and the switches 15, 15 comprise elements of a conventional multiband radio receiver, it is unnecessary to illustrate the details of the receiver circuit. Hence only one connection to each of the sections of the switches 15, 15 is shown from each of the windings 12, 12.

The tuning mechanism also includes a longitudinally movable member on carriage 17 for controlling each of the tuning means 11 and 11'. The carriage 17 is provided with a transverse end plate 18 which is attached to three longitudinal rods 16 of circular cross section slidably mounted in three accurately conforming bores 19 in a pair of vertically disposed transverse plates 20, 20 which constitute a portion of the framework 10. A pair of coil springs 21, 21 (see Fig. 1) are fastened to lugs 22, 22 on opposite ends of the end plate 18 of the carriage 17 and to lugs 24, 24 on the forward portion of the framework 10, normally to maintain the end plate 18 of the carriage in engagement with the rear portion of the framework as shown in the broken-line construction in Figs. 1 and 3. Each core 13 of each tuning means 11 and 11' includes a semi-rigid threaded extension 26 which passes through a suitable aperture in the end plate 18 and is secured thereto by means of a pair of nuts 25, 25 so that movement of carriage 17 is effective to adjust the position of the core with respect to the corresponding winding 12 of the tuning device 11 or 11'. The described individual adjustment of each core 13 may be employed for alignment purposes.

The tuning arrangement also includes a plurality of groups of longitudinally movable members, each of which is movable independently

of any other member and is adapted to actuate the carriage 17 and both of the associated tuning means 11, 11 and 11', 11'. These members comprise pairs of slides 30, 30', each slide being slidably mounted in a rectangular guiding aperture 31 in each of the transverse plates 20. (see Fig. 4). Each slide includes a cam 33 having a steep shoulder portion 34 at the terminal end of the cam. A biasing means in the form of a coil spring 35 is suspended between the rearmost end of each slide 30, 30' and the front transverse plate 20 for the purpose of normally retaining the slide in an inoperative position wherein the shoulder 34 engages the forward plate 20 in the manner illustrated in Fig. 4 of the drawings. The forward end of each of these slides has secured thereto a spool-shaped member 32 for a purpose to be explained subsequently. An adjusting screw 39, which is adapted freely to pass through relatively large apertures 40, 40 in the transverse plates 20, 20, is adjustably mounted in threaded apertures 41, 41 in a bifurcated lug 42 on each of the slides 30. The position of the rear end of each screw 39 with respect to its co-operating lug 42 varies with each slide, so that each slide is adapted to tune the associated receiver to a different predetermined frequency, as will be made clear hereinafter.

The tuning mechanism also comprises a plurality of manually operable push-button elements 45 which correspond in number to the number of groups or pairs of slides 30, 30'. Each push-button element is disposed individually to engage and to move any one of the slides 30 or 30' of a different pair or group from a non-operative position to an operative position for selectively adjusting the tuning means to a corresponding preselected frequency, specifically to a selected frequency within a selected frequency band, as will be explained in detail subsequently. Each push-button element 45 is in the form of a bell-crank lever which is pivotally mounted on a lug 46 and extends through an elongated aperture 47 (see Fig. 3) in a channel 48 on the upper front portion of the framework 10. The lug 46 comprises a portion of a transversely movable shifting bar 49 which is slidably mounted in the channel 48 (see also Fig. 4).

Each push-button element 45 includes a forwardly extending arm 50 having a finger pad 51 at the free end thereof, which may carry a transmitting station identifying legend, and a downwardly extending arm 53 having an arcuate contact surface 54 at its lower end. A relatively short arm 55 on each push-button element 45 extends rearwardly of the pivot and includes a small aperture 56 at the end thereof (see Figs. 3 and 5). A flat tongue 57 having a bifurcated end 58 is hooked into the aperture 56 of each push-button element while the opposite end of the tongue slidably extends through an opening 69 in a channel 61 which is attached to the framework 10 by suitable fasteners 63 (see Fig. 1). A washer 65 is slidably mounted on each tongue 57 and is maintained in resilient engagement with the corresponding arm 55 by means of a coil spring 67 which encompasses the tongue and exerts a thrust on both the slidable washers 65 and the fixed channel 61.

Each push-button element 45 has an upright non-operative position in which the finger pad 51 is at its highest elevation and also a depressed operative position wherein the pad is at a lower elevation, as illustrated in Figs. 3 and 4 of the

drawings. In either of the two positions the arm 55 and the tongue 57 are not disposed in a straight line. Because of this factor and also because of the biasing action afforded by the spring 67, each combination comprising the pivoted portion of a push-button element 45, its arm 55, the tongue 57, the spring 67, and the washer 65 constitutes an effective means for yieldably restraining each push-button element normally in an upright position prior to the operation thereof and in a depressed operative position after the operation thereof.

It will be noted in Figs. 4 and 5 that when a push-button element 45 is in an inoperative position, the arm 53 thereof extends substantially vertically and the arcuate contact surface 54 is aligned with the reduced diameter portion of the member 32 on one of the pairs of slides 30. It will be made clear hereinafter that, when a push-button element 45 is in an alternative position as represented by the broken-line construction of Fig. 4, it is also oriented so that it is adapted to make operative engagement with the other slide 30' of the pair of slides.

As previously mentioned, the coil spring 35 normally maintains each of the slides 30 or 30' in the inoperative position which is illustrated in Fig. 4 of the drawings. In the operative position which is illustrated for one of the slides in Fig. 3, the actuated slide is held in its rearmost position by means of a latch 70. The latch 70 comprises a bar or angle iron which extends transversely of the framework 10 and is pivotally mounted thereon by means of a pair of pins 71, 71' (see Figs. 1 and 4) which are connected to lugs 72, 72' at the extreme ends of the bar. The pins 71 are rotatably held in bearing apertures in the framework 10. A pair of coil springs 74, 74' are attached at their extremities to the rearmost transverse plate 20 and to a transverse plate or hook 75 on the latch 70 so that when a slide 30 or 30' is in an actuated or operative position, the hook 75 is resiliently held against the shoulder 34 of that slide.

The tuning mechanism of the instant invention also comprises means for providing relative movement between the slide 30 or 30' and the push-button elements 45 for selectively and individually establishing operative relations between the plurality of push-button elements and any corresponding slide of the pairs of slides in order to determine in which one of the frequency bands the apparatus is tuned. This means includes a knob 78 which is attached to a shaft 79 that is rotatably supported in a pair of brackets 80, 80' which are attached to one side of the framework 10 (see Fig. 1). A linkage 81 is attached at one of its ends to the shaft 79 while the other end thereof retains a horizontally disposed pin 83 (see also Fig. 4) which projects rearwardly through an elongated opening 84 in the transversely movable shifting bar 49. The pin 83 is also adapted to slide in a substantially U-shaped opening 85 in a transverse portion 86 of a member 87, the latter being pivotally secured to the framework 10 by a bolt and nut arrangement 90. The transverse length of the opening 85 is substantially twice that of the other opening 84 in the shifting bar 49. Surfaces 91, 91' and the opening 85 comprise a cam portion which serves a purpose to be explained subsequently. The pivoted member 87 includes a rearwardly extending foot 93, the free end of which is adapted to engage the transverse hook 75 of the latch 70.

The shaft 79 is also connected to an additional linkage 88 (Fig. 1) which is in turn coupled to a shaft 96 that is mounted in suitable brackets 97, 97' on the framework 10. The rotary elements 5 of the switches 15, 15' are operated by the shaft 96 in such a manner that switch 15 is closed when the switch 15' is open and vice versa.

The tuning mechanism also includes a manually operable continuously adjustable member 10 which is adapted to adjust the tuning means of the receiver to any frequency within each of the pair of frequency bands. This member comprises a slide 100 which is essentially similar in construction to either of the described slides 30 or 30'. At the forward end of slide 100 is a spool-shaped member 101 (see Figs. 1 and 4) which is considerably longer than the member 32 on any of the other slides. An externally threaded hollow sleeve 103 is adjustably mounted on a lug 104 on the top of the slide 100. Slide 100 has a cam portion 105, a shoulder 106, and a coil spring 107 which are similar to corresponding members of the slide 30. The hollow sleeve 103 has a rectangular bore and the sleeve is adapted to slide on a rod 108 of similar cross section so that rotation of the rod about its axis alters the position of the sleeve on the lug 104. The rod 108 also extends through a bearing 110 in the front of the framework and carries at its front end a sleeve 111 (see Fig. 1) and an adjusting knob 112 (see Fig. 4) so that rotation of the knob is effective to adjust the hollow sleeve 103 longitudinally of the lug 104. A frequency-indicating element or pointer 114 is slidably mounted on a transverse plate 115 and is actuated by a cord 116 and a pulley 117 which are associated with a winding drum 109 which is attached to the rod 108.

Centrally located between the push-button elements 45 at the front of the tuning mechanism is an additional push-button element 120 which is disposed selectively to place the above-described continuously adjustable member in cooperative relation with either set of the tuning means 11, 11' or 11', 11' to permit the apparatus to be tuned to any frequency within each of the pair of frequency bands. Push-button element 120 is mounted on the shifting bar 49 and is similar to the previously described push-button elements 45, hence the description thereof need not be repeated.

Considering now the operation of the above-described tuning mechanism, it will be initially assumed that all the push-button elements 45 are in an upright or inoperative position corresponding to that of the single push-button element which is illustrated in full lines in Fig. 4 of the drawings. It will also be assumed that the switches 15, 15' are so positioned that only the upper set of tuning means 11, 11' is energized and operatively connected to the circuits of the radio receiver. As one of the push-button elements is depressed, for example the element shown in full lines in Fig. 4, it rotates about its pivot thereby causing contact surface 54 of the arm 55 to be brought into engagement with the member 32 on the end of the slide 30 of one of the pairs of slides. This pushes the slide 30 rearwardly in its guiding apertures 31, 31' against the resistance of the coil spring 35. Cam 33 comes into engagement with the hook 75 of the latch 70 and depresses it to the position represented in broken lines in Fig. 4. Additional movement of the slide 30 permits the springs 74, 74' to pull the hook 75 firmly against the shoulder 34 at 75 the back of the cam so that the slide is maintained

in an operative position. During the above-mentioned rearward movement of the slide 30, the adjusting screw 39 on the top of the slide passes through the aperture 40 in the rearmost transverse plate 20 and is brought into engagement, in the manner illustrated for a slide 30' in Fig. 1, with the end plate 18 on the carriage 17. Consequently, the position of the end of the adjusting screw 39 with relation to its supporting bracket 42 determines the extent of the longitudinal movement of the carriage 17 and hence the position of the cores 15, 15 with respect to the windings 12, 12. This in turn tunes the receiver to a selected frequency within a selected frequency band, for example the broadcast band, as determined by the particular push-button element which is operated.

The eccentric arrangement including the spring 67 on the actuated push-button element is effective to retain that element in a depressed position, and its appearance with respect to the remaining push-button elements indicates the frequency in the particular band to which the apparatus is tuned, as will be appreciated from the representation of Fig. 1 of the drawings.

To tune the receiver to a station in a different frequency band, such as the frequency-modulation band, the knob 78 is rotated clockwise, as viewed in Fig. 1. This turns the shaft 79 and operates the linkage 81 from the full-line position illustrated in Fig. 4 toward the broken-line position. As the linkage moves to the right, the pin 83 at the free end of the link moves freely in the elongated opening 84 in the shift bar 49 while at the same time engaging the left-hand cam portion 91 in such a manner that the transverse portion 86 of the member 87 is elevated. This causes the rearwardly extending foot 93 to move to the position represented diagrammatically in broken-line construction in Fig. 4, thus tripping the latch 70 and releasing the shoulder 34 of the actuated slide 30 from engagement with the latch hook 75. The spring 35 then returns the slide 30 to its original position and the thrust exerted on the arm 53 by the member 32 of the slide rocks the push-button element 45 to its initial elevated position.

As the movement of the pin 83 continues to the right, it engages the right-hand end of the elongated opening 84 and forces the shifting bar 49 against the resistance of the plurality of members including the springs 67 from its initial position to a new position shown generally in broken lines in Fig. 4. Since the push-button elements are mounted on the shifting bar 49, the former are displaced as a unit to the right to the new position represented diagrammatically by the broken-line construction in Fig. 4 for a single push-button element. When the push-button elements 45 are in this new position, the pin 83 is in the upper right-hand portion of the elongated opening 85 and the member 87 and the latch 70 are returned to their original positions by the action of the coil springs 74. The final portion of movement of the shifting bar 49 to the above-described new position is assisted by the action of the members including the plurality of coil springs 67 since they then exert a component of force to the right. Elements 45 and the shifting bar 49 are likewise resiliently maintained in this new position by the thrust which is exerted by the plurality of springs 67.

The above-mentioned switching operation is effective to rotate the shaft 96 and to modify the

positions of the switches 15, 15 so that the windings 12, 12 of the upper set of tuning means 11, 11 are no longer energized while the corresponding windings of the lower set of tuning means 11', 11' are operatively coupled to the circuits of the receiver.

In the new operating position the lower depending arm 53 of each push-button element 45 is aligned with the other slide 30' of its corresponding pair of slides. Accordingly, it will be seen that the arrangement including the shifting bar 49 comprises a means for selectively and individually establishing operative relations between the plurality of push-button elements 45 and any corresponding slides of the pair of slides to determine to which one of the frequency bands the apparatus is tuned. It will also be apparent that the pin 83 and the elongated openings 84 and 85 comprise a lost-motion means which is utilized for shifting the push-button elements relative to the slides.

The depression of a push-button element 45 will now cause the arm 53 thereof to actuate one of the slides 30' of the pairs of slides. The movement of this slide operates the carriage 17 and the tuning means 11', 11' in the previously described manner in connection with one of the slides 30 so that the receiver is tuned to a selected frequency in the second of the frequency bands. Operation of a different push-button element 45 causes its corresponding slide 30' to be actuated and the rearward movement brings its cam into engagement with the latch 75 and releases the previously actuated slide from the influence of the latch 70. Movement of the last-mentioned actuated slide to the end of its rearward travel causes it to be latched so that the carriage 17 is adjusted in a manner to tune the receiver to a different frequency.

If so-called manual or continuously adjustable tuning is desired, the push-button element 120 is depressed, thus bringing the arm 121 thereof into engagement with the member 101 on the slide 100. Slide 100 is moved rearwardly and this causes sleeve 103 to slide along the rod 108. Cam 105 operates the latch 70 and releases all previously actuated slides before the slide 100 is locked in an operative position by the engagement of the hook 75 with the shoulder 106. Adjustment of the knob 112 causes the sleeve 103 to rotate within the lug 104 while sliding along the rod 108. Engagement of the end of rotary sleeve 103 with the plate 18 on the carriage 17 adjusts the position of the tuning means so that the receiver may be tuned by manual adjustment to any frequency in the specific frequency band which is selected, as determined by the position of the shifting bar 49. Rotation of the rod 108 also turns the drum 109 (see Fig. 1) and operates the frequency-indicating element 114 in the well-known manner.

It will be observed in Fig. 4 that in either of the positions illustrated for the arm 121 of the push-button element 120, the arm is adapted to engage the spool-shaped member 100 because of the length of the latter. Actuation of the shifting bar 49 by rotation of knob 48 is effective to release any previously actuated slides 30 or 30' or 100 and to shift the arm 121 of push-button element 120 to either of the positions illustrated diagrammatically in Fig. 4 so that tuning may be effected in either of the pair of frequency bands. It will be apparent that the frequency-indicating element 114 is actuated only when the knob 112 is rotated.

For some applications, push-button operation only may be sufficient, in which case the continuously adjustable tuning mechanism may be dispensed with. While the invention has been described in connection with variable inductance detuning elements, it will be manifest that other types of tuning may be employed with an arrangement of the general character described. However, the described mechanism is particularly advantageous in connection with inductance-tuned wave-signal translating apparatus since the longitudinally adjustable cores in the tuning means and the co-operating mechanical portions thereof assure precise adjustment of frequency setting. The adjusting screws 39 and 103 may be set very accurately and conveniently from the front of the tuning mechanism. Wearing parts which affect the accuracy are few in number and are limited to the contacting surfaces of the adjusting screws 39 and 103, the transverse plate 18 on the carriage 17, and also the hook 15 and the shoulders 34 and 106 which co-operate therewith. The absence of backlash in the adjustable and moving parts causes the mechanism to be particularly useful in connection with inductance-tuned receivers. The use of wear-resisting materials at the above-mentioned points assures a high degree of tuning accuracy throughout the life of the arrangement.

While the described mechanical tuning mechanism possesses certain advantages, the invention is not necessarily limited only to mechanical structures. In a mechanical arrangement, however, relatively few electrical tuning means are required and the switching problems are greatly minimized. As a result the tuning means may be mounted in a very compact fashion. This is particularly advantageous where space requirements for the tuning mechanism are severe.

While the invention has been described in connection with groups of slides comprising pairs of slides 30, 30', it will be manifest that a group of such slides may include three or more slides. Accordingly the shifting mechanism including the shifting bar 49 will have a corresponding number of positions instead of the two mentioned hereinbefore.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A tuning mechanism for a wave-signal translating apparatus including adjustable means for tuning said apparatus to a plurality of preselected frequencies comprising: a plurality of groups of actuating members, each member thereof being movable independently of any other member from a nonoperative position to an operative position and adapted when moved to said operative position to effect a preselected adjustment of said tuning means; a manually operable element for each of said groups of actuating members, each of said manually operable elements being adapted individually to engage and to move any one of said actuating members of an individual group thereof from its nonoperative position to its operative position for selectively adjusting said tuning means to a corresponding preselected frequency; means for

latching any actuated member in said operative position thereof; means on each of said actuating members for tripping said latching means and releasing any actuated member which is latched in said operative position thereof when any actuating member is operated from said nonoperative position thereof to said operative position thereof; means for selectively establishing operative relations between each of said manually operable elements and any selected one of said actuating members of a group individual thereto so that said tuning means may be selectively adjusted to any of a plurality of preselected frequencies by each of said manually operable elements; and means controlled by said means for establishing operative relations for tripping said latching means and releasing any actuated member latched in said operative position thereof prior to the establishment of said operative relations between said actuating members and said manually operable elements.

2. A tuning mechanism for a wave-signal translating apparatus including adjustable means for tuning said apparatus to a plurality of preselected frequencies comprising: a plurality of groups of actuating members, each member thereof being movable independently of any other member from a nonoperative position to an operative position and adapted when moved to said operative position to effect a preselected adjustment of said tuning means; a manually operable element for each of said groups of actuating members, each of said manually operable elements being adapted individually and directly to engage and to move any one of said actuating members of an individual group thereof from its nonoperative position to its operative position for selectively adjusting said tuning means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means for selectively establishing operative relations between each of said manually operable elements and any selected one of said actuating members of a group individual thereto so that said tuning means may be selectively adjusted to any of a plurality of preselected frequencies by each of said manually operable elements; and means controlled by said means for establishing operative relations for tripping said latching means and releasing any actuated member latched in said operative position thereof prior to the establishment of said operative relations between said actuating members and said manually operable elements.

3. A tuning mechanism for a wave-signal translating apparatus including adjustable means for tuning said apparatus to a plurality of preselected frequencies comprising: a plurality of groups of actuating members, each member thereof being movable independently of any other member from a nonoperative position to an operative position and adapted when moved to said operative position to effect a preselected adjustment of said tuning means; a manually operable element for each of said groups of actuating members, each of said manually operable elements being adapted individually to engage and to move any one of said actuating members of an individual group thereof from its nonoperative

ative position to its operative position for selectively adjusting said tuning means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means for selectively and individually establishing operative relations between each of said manually operable elements and any corresponding members of said groups of actuating members so that said tuning means may be selectively adjusted to any selected frequency in a predetermined group of frequencies; and means controlled by said means for establishing operative relations for tripping said latching means and releasing any actuated member latched in said operative position thereof prior to the establishment of said operative relations between said actuating members and said manually operable elements.

4. A tuning mechanism for a wave-signal translating apparatus including adjustable means for tuning said apparatus to a plurality of preselected frequencies comprising: a plurality of pairs of actuating members, each member thereof being movable independently of any other member from a nonoperative position to an operative position and adapted when moved to said operative position to effect a preselected adjustment of said tuning means; a manually operable element for each of said pairs of actuating members, each of said manually operable elements being adapted individually to engage and to move any one of said actuating members of an individual pair thereof from its nonoperative position to its operative position for selectively adjusting said tuning means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means for selectively establishing operative relations between each of said manually operable elements and any selected one of said actuating members of a pair individual thereto so that said tuning means may be selectively adjusted to any of a pair of preselected frequencies by each of said manually operable elements; and means controlled by said means for establishing operative relations for tripping said latching means and releasing any actuated member latched in said operative position thereof prior to the establishment of said operative relations between said actuating members and said manually operable elements.

5. A tuning mechanism for a wave-signal translating apparatus including adjustable means for tuning said apparatus to a plurality of preselected frequencies comprising: a plurality of groups of actuating members, each member thereof being movable independently of any other member from a nonoperative position to an operative position and adapted when moved to said operative position to effect a preselected adjustment of said tuning means; a manually operable element for each of said groups of actuating members, each of said manually operable

elements being adapted individually to engage and to move any one of said actuating members of an individual group thereof from its nonoperative position to its operative position for selectively adjusting said tuning means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means providing relative movement between said actuating members and said manually operable elements for selectively and individually establishing operative relations between each of said manually operable elements and any corresponding members of said groups of actuating members so that said tuning means may be selectively adjusted to any selected frequency in a predetermined group of frequencies; and means controlled by said means for providing said relative movement for tripping said latching means and releasing any actuated member latched in said operative position thereof prior to the establishment of said relative movement and said operative relations between said actuating members and said manually operable elements.

6. A tuning mechanism for a wave-signal translating apparatus including adjustable means for tuning said apparatus to a plurality of preselected frequencies comprising: a plurality of groups of actuating members, each member thereof being movable independently of any other member from a nonoperative position to an operative position and adapted when moved to said operative position to effect a preselected adjustment of said tuning means; adjustable means on each of said actuating members for engagement with said tuning means to modify the adjustment of said tuning means; a manually operable element for each of said groups of actuating members, each of said manually operable elements being adapted individually to engage and to move any one of said actuating members of an individual group thereof from its nonoperative position to its operative position for selectively adjusting said tuning means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means for selectively establishing operative relations between each of said manually operable elements and any selected one of said actuating members of a group individual thereto so that said tuning means may be selectively adjusted to any of a plurality of preselected frequencies by each of said manually operable elements; and means controlled by said means for establishing operative relations for tripping said latching means and releasing any actuated member latched in said operative position thereof prior to the establishment of said operative relations between said actuating members and said manually operable elements.

7. A tuning mechanism for a wave-signal translating apparatus including longitudinally adjustable means for tuning said apparatus to a plurality of preselected frequencies comprising:

a longitudinally movable member for controlling said tuning means; a plurality of groups of actuating members, each member thereof being longitudinally movable independently of any other actuating member from a nonoperative position to an operative position and adapted when moved to said operative position to actuate said control member to effect a preselected adjustment of said tuning means; a manually operable element for each of said groups of actuating members, each of said manually operable elements being adapted individually to engage and to move any one of said actuating members of an individual group thereof from its nonoperative position to its operative position thereby to actuate said control member for selectively adjusting said tuning means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means for producing transverse relative movement between said actuating members and said manually operable elements for selectively establishing operative relations between each of said manually operable elements and any selected one of said actuating members of a group individual thereto so that said tuning means may be selectively adjusted to any of a plurality of preselected frequencies by each of said manually operable elements; and means controlled by said means for producing said transverse relative movement for tripping said latching means and releasing any actuated member latched in said operative position thereof prior to the establishment of said transverse relative movement and said operative relations between said actuating members and said manually operable elements.

8. A tuning mechanism for a wave-signal translating apparatus including longitudinally adjustable means for tuning said apparatus to a plurality of preselected frequencies comprising: a longitudinally movable carriage for controlling said tuning means; a plurality of groups of actuating members, each member thereof being longitudinally movable independently of any other actuating member from a nonoperative position to an operative position and adapted when moved to said operative position to actuate said carriage to effect a preselected adjustment of said tuning means; a push-button element for each of said groups of actuating members, each of said push-button elements being adapted individually to engage and to move any one of said actuating members of an individual group thereof from its nonoperative position to its operative position to actuate said carriage for selectively adjusting said tuning means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means for producing transverse relative movement between said actuating members and said push-button elements for selectively establishing operative relations between each of said push-button ele-

ments and any selected one of said actuating members of a group individual thereto so that said tuning means may be selectively adjusted to any of a plurality of preselected frequencies by each of said push-button elements; biasing means for maintaining said carriage in co-operative relation with any selected one of said actuating members; and means controlled by said means for producing said transverse relative movement for tripping said latching means and releasing any actuated member latched in said operative position thereof prior to the establishment of said transverse relative movement and said operative relations between said actuating members and said push-button elements.

9. A tuning mechanism for a wave-signal translating apparatus including adjustable means for tuning said apparatus to a plurality of preselected frequencies comprising: a plurality of groups of actuating members, each member thereof being movable independently of any other member from a nonoperative position to an operative position and adapted when moved to said operative position to effect a preselected adjustment of said tuning means; biasing means for normally retaining said actuating members in said nonoperative position; means for latching any actuated member in said operative position thereof; a manually operable element for each of said groups of actuating members, each of said manually operable elements being adapted individually to engage and to move any one of said actuating members of an individual group thereof from its nonoperative position to its operative position for selectively adjusting said tuning means to a corresponding preselected frequency; means on each of said actuating members for tripping said latching means and releasing any actuated member which is latched in said operative position thereof when any actuating member is operated from said nonoperative position thereof to said operative position thereof; means for selectively establishing operative relations between each of said manually operable elements and any selected one of said actuating members of a group individual thereto so that said tuning means may be selectively adjusted to any of a plurality of preselected frequencies by each of said manually operable elements; and means controlled by said means for establishing operative relations for tripping said latching means and releasing any actuated member latched in said operative position thereof prior to the establishment of said operative relations between said actuating members and said manually operable elements.

10. A tuning mechanism for a wave-signal translating apparatus including adjustable means for tuning said apparatus to a plurality of preselected frequencies comprising: a plurality of groups of actuating members, each member thereof being movable independently of any other member from a nonoperative position to an operative position and adapted when moved to said operative position to effect a preselected adjustment of said tuning means; a manually operable element for each of said groups of actuating members, each of said manually operable elements being adapted individually to engage and to move any one of said actuating members of an individual group thereof from its nonoperative position to its operative position for selectively adjusting said tuning means to a corresponding preselected frequency; means for latching any actuated member in said

operative position thereof; means on each of said actuating members for tripping said latching means and releasing any actuated member which is latched in said operative position thereof when any actuating member is operated from said nonoperative position thereof to said operative position thereof; means providing relative movement between said actuating members and said manually operable elements for selectively and individually establishing operative relations between each of said manually operable elements and any corresponding members of said groups of actuating members so that said tuning means may be selectively adjusted to any selected frequency in a predetermined group of frequencies; and means controlled by said last-named means for tripping said latching means and releasing any actuated member latched in said operative position thereof prior to the establishment of operative relations between said actuating members and said manually operable elements.

11. A tuning mechanism for a wave-signal translating apparatus including adjustable means for tuning said apparatus to a plurality of preselected frequencies comprising: a plurality of groups of actuating members, each member thereof being movable independently of any other member from a nonoperative position to an operative position and adapted when moved to said operative position to effect a preselected adjustment of said tuning means; biasing means for normally retaining said actuating members in said nonoperative position; means for latching any actuated member in said operative position thereof; a manually operable element for each of said groups of actuating members, each of said manually operable elements being adapted individually to engage and to move any one of said actuating members of an individual group thereof from its nonoperative position to its operative position for selectively adjusting said tuning means to a corresponding preselected frequency; means on each of said actuating members for tripping said latching means and releasing any actuated member which is latched in said operative position thereof when any actuating member is operated from said nonoperative position thereof to said operative position thereof; means including lost-motion means for shifting said manually operable elements relative to said actuating members for selectively establishing operative relations between each of said manually operable elements and any selected one of said actuating members of a group individual thereto so that said tuning means may be selectively adjusted to any of a plurality of preselected frequencies by each of said manually operable elements; and a pivoted member having a cam portion which is arranged for actuation by said lost-motion means to trip said latching means and to release any actuated member latched in said operative position thereof prior to the shifting of said manually operable elements relative to said actuating members.

12. A tuning mechanism for a wave-signal translating apparatus including adjustable means for tuning said apparatus to a plurality of preselected frequencies comprising: a plurality of groups of actuating members, each member thereof being movable independently of any other member from a nonoperative position to an operative position and adapted when moved to said operative position to effect a preselected adjustment of said tuning means; a manually operable element for each of said groups of

actuating members, each of said manually operable elements being adapted individually to engage and to move any one of said actuating members of an individual group thereof from its nonoperative position to its operative position for selectively adjusting said tuning means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means for selectively establishing operative relations between each of said manually operable elements and any selected one of said actuating members of a group individual thereto so that said tuning means may be selectively adjusted to any of a plurality of preselected frequencies by each of said manually operable elements; means controlled by said means for establishing operative relations for tripping said latching means and releasing any actuated member latched in said operative position thereof prior to the establishment of operative relations between said actuating members and said manually operable elements; and means for yieldably restraining each of said manually operable elements normally in a nonoperative position prior to operation thereof and in an operative position after operation thereof to indicate the frequency to which said apparatus is tuned.

13. A tuning mechanism for a wave-signal translating apparatus including adjustable means for tuning said apparatus to a plurality of preselected frequencies comprising: a plurality of groups of actuating members, each member thereof being movable independently of any other member from a nonoperative position to an operative position and adapted when moved to said operative position to effect a preselected adjustment of said tuning means; a pivotally mounted manually operable push-button element for each of said groups of actuating members, each of said manually operable push-button elements having an upright nonoperative position and a depressed operative position and being adapted individually to engage and to move any one of said actuating members of an individual group thereof from its nonoperative position to its operative position for selectively adjusting said tuning means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means for selectively establishing operative relations between each of manually operable push-button elements and any selected one of said actuating members of a group individual thereto so that said tuning means may be selectively adjusted to any of a plurality of preselected frequencies by each of said manually operable elements; means controlled by said means for establishing operative relations for tripping said latching means and releasing any actuated member latched in said operative position thereof prior to the establishment of operative relations between said actuating members and said push-button ele-

ments; and eccentric means co-operating with said push-button elements for yieldably restraining each of said manually operable push-button elements normally in said nonoperative position prior to operation thereof and in said operative position after operation thereof to indicate the frequency to which said apparatus is tuned.

14. A tuning mechanism for a wave-signal translating apparatus including adjustable means for tuning said apparatus to a plurality of preselected frequencies comprising: a plurality of groups of actuating members, each member thereof being longitudinally movable independently of any other member from a nonoperative position to an operative position and adapted when moved to said operative position to effect a preselected adjustment of said tuning means; a manually operable element for each of said groups of actuating members, each of said manually operable elements being adapted individually to engage and to move any one of said actuating members of an individual group thereof from its nonoperative position to its operative position for selectively adjusting said tuning means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means for selectively and simultaneously shifting said push-button elements transversely of said groups of actuating members to any one of a plurality of positions for selectively and individually establishing operative relations in any one of said plurality of transverse positions between said manually operable elements and any corresponding members of said groups of actuating members so that said tuning means may be selectively adjusted to any selected frequency in a predetermined different group of frequencies; means controlled by said shifting means for tripping said latching means and releasing any actuated member latched in said operative position thereof prior to the establishment of said operative relations between said actuating members and said manually operable elements; and eccentric biasing means for yieldably restraining each of said manually operable elements normally in a nonoperative position prior to operation thereof and in an operative position after operation thereof and for yieldably maintaining said shifting means in any selected one of said plurality of transverse positions.

15. A tuning mechanism for a wave-signal translating apparatus including a plurality of adjustable means for tuning said apparatus to a plurality of preselected frequencies within any one of a plurality of frequency bands comprising: a plurality of groups of actuating members, each member thereof being movable independently of any other member from a nonoperative position to an operative position and adapted when moved to said operative position to effect a preselected adjustment of said tuning means; a manually operable element for each of said groups of actuating members, each of said manually operable elements being adapted individually to engage and to move any one of said actuating members of an individual group thereof from its nonoperative position to its operative position for selectively adjusting said tuning

means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means for selectively and individually establishing operative relations between said plurality of manually operable elements and any corresponding members of said groups of actuating members so that said tuning means may be selectively adjusted to any preselected frequency in a predetermined different group of frequencies; means operatively associated with said last-named means for selectively controlling any one of said plurality of tuning means to determine in which one of said frequency bands said apparatus is tuned and means controlled by said means for establishing operative relations for tripping said latching means and releasing any actuated member latched in said operative position thereof prior to the establishment of said operative relations between said actuating members and said manually operable elements.

16. A tuning mechanism for a wave-signal translating apparatus including a plurality of adjustable inductance means for tuning said apparatus to a plurality of preselected frequencies within any one of a plurality of frequency bands comprising: a plurality of groups of actuating members, each member thereof being movable independently of any other member from a nonoperative position to an operative position and adapted when moved to said operative position to effect a preselected adjustment of said inductance means; a manually operable element for each of said groups of actuating members, each of said manually operable elements being adapted individually to engage and to move any one of said actuating members of an individual group thereof from its nonoperative position to its operative position for selectively adjusting said inductance means; means controlled by said shifting means for latching any actuated member in said operative position thereof; means on each of said actuating members for tripping said latching means and releasing any actuated member which is latched in said operative position thereof when any actuating member is operated from said nonoperative position thereof to said operative position thereof; means for selectively and individually establishing operative relations between said plurality of manually operable elements and any corresponding members of said groups of actuating members so that said inductance means may be selectively adjusted to any preselected frequency in a predetermined different group of frequencies; switching means operatively associated with said last-named means for selectively controlling the energization of any one of said plurality of inductance means to determine in which one of said frequency bands said apparatus is tuned and means controlled by said means for establishing operative relations for tripping said latching means and releasing any actuated member latched in said operative position thereof prior to the establishment of said operative relations between said actuating members and said manually operable elements.

17. A tuning mechanism for a wave-signal translating apparatus including longitudinally adjustable tuning means for tuning said apparatus

atus to a plurality of preselected frequencies comprising: a longitudinally movable member for controlling said tuning means; a plurality of groups of actuating members, each member thereof being longitudinally movable independently of any other member from a nonoperative position to an operative position and adapted when moved to said operative position to actuate said control member to effect a preselected adjustment of said tuning means; a manually operable push-button element for each of said groups of actuating members, each of said push-button elements being adapted individually to engage and to move any one of said actuating members of an individual group thereof from its nonoperative position to its operative position for selectively adjusting said tuning means to a corresponding preselected frequency; means for latching any actuated member in said operative position thereof; means on each of said actuating members for tripping said latching means and releasing any actuated member which is latched in said operative position thereof when any actuating member is operated from said nonoperative position thereof to said operative position thereof; means for selectively and simultaneously shifting said push-button elements transversely of said groups of actuating members to any one of a plurality of positions for selectively and individually establishing operative relations between said plurality of push-
